UNITED STATES PATENT OFFICE.

MAE R. DAY, OF CASPER, WYOMING.

BUTTON SNAP.

Application filed July 17, 1923. Serial No. 652,143.

To all whom it may concern:

Be it known that I, MAE R. DAY, a citizen of the United States, residing at Casper, in the county of Natrona and State of 5 Wyoming, have invented a new and useful Button Snap, of which the following is a specification.

This invention relates to garment fasteners and more particularly to those of the 10 separable type.

The object of the invention is to provide a simple and inexpensive device of this character the parts of which when engaged will remain secure until manually released.

15 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

20 In the accompanying drawings:—

Figure 1 represents a plan view of one member of the fastener.

Fig. 2 is a transverse section thereof taken on the line 2—2 of Fig. 1.

25 Fig. 3 is a plan view of the other member of the fastener.

Fig. 4 is a transverse section taken on the line 4—4 of Fig. 3; and

30 Fig. 5 is a longitudinal section showing the fastener with the members in closed position.

In the embodiment illustrated the member 1 is composed of sheet metal folded to form a double walled structure with the walls 40 2 and 3 spaced apart and the wall 2 extended at one end beyond the adjacent end of wall 3. The wall 2 has a hump 4 formed therein by indenting it which indentation or hump extends into a slot 5, arranged longitudinally in wall 3 and opening through the end of said wall located adjacent the extension in wall 2. This member 1 is provided at its four corners with apertures 6 to receive the threads for connecting it to 45 the garment.

The cooperating member 10 shown in Figs. 3 and 4 is composed of a plate of metal having apertures 11 at its corners for securing it to a garment and provided with an out struck tongue 12 the neck 13 of which is offset so that when the device is applied said tongue will enter the slot 5 of the cooperating member 1 and a hump 14 formed therein will fit over the hump 4 of member 1 and assist in securing the members in 55 engaged position. The tongue 12 is of a diameter greater than slot 5 and is designed to be entered through the open end of said slot into the position shown in Fig. 5 and to snap over the nib or hump 4. 60

From the above description it will be obvious that the members 1 and 10 when engaged in the manner above set forth will be securely held against accidental release and cannot be disengaged until slid manually one on the other to release tongue 12 from slot 5. 65

Various changes in the form, shape, proportion and other minor details of construction may be made without departing from 70 the principle or sacrificing any of the advantages of the claimed invention.

I claim:—

A separable garment fastener comprising a double walled member having an open 80 slot in one wall the other wall being unyieldable and having a nib extending into said slot, and a cooperating member having an offset spring tongue equipped with a socket, said tongue being of a diameter 85 greater than the slot in the other member and designed to enter said member between the walls thereof, said tongue having a neck operating in said slot, the socket in the tongue being designed to fit over the 90 nib in the other member.

In testimony that I claim the foregoing as my own, I have hereto affixed my signature in the presence of two witnesses.

MAE R. DAY.

Witnesses:

AGNES MARSHALL,
GEO. W. FERGUSON.
